UNITED STATES PATENT OFFICE

FRED W. NOFFS, OF BELLWOOD, ILLINOIS

ELECTRIC-CIRCUIT CONTROLLER

Original application filed August 4, 1928, Serial No. 297,567. Divided and this application filed June 19, 1929. Serial No. 372,168.

This invention relates to improvements in electric circuit controllers and is a division of my application Serial Number 297,567, filed August 4, 1928, for signalling apparatus for aeroplanes or the like.

The principal object of the invention is to provide a controlling or switching mechanism for independently controlling a plurality of electric signalling circuits, altho 10 the invention is not limited particularly to signalling circuits.

Another object of the invention is to provide a controlling mechanism the individual switch members of which can be easily operated and which are arranged in compact relation in a suitable receptacle which may be mounted at a convenient position with respect to the operator, such as in the cockpit of an aeroplane.

20 Other objects relate to various features of construction and arrangement of parts which will be apparent from a consideration of the following specifications and accompanying drawings, wherein;

25 Figure 1 is a top plan view of a controller with the cover of the enclosure removed.

Fig. 2 is a transverse section taken in line 2—2 of Fig. 1.

Fig. 3 is a longitudinal sectional view 30 taken in line 3—3 of Fig. 1.

Fig. 4 is a sectional view taken on line 4—4 of Fig. 1.

Fig. 5 is a sectional view taken on line 5—5 of Fig. 1.

35 Fig. 6 is a sectional view taken on line 6—6 of Fig. 1.

Fig. 7 is a sectional view taken on line 7—7 of Fig. 1.

Fig. 8 is a perspective view of one of the 40 switch slide members.

Fig. 9 is a sectional view of a slide member taken on line 9—9 of Fig. 8.

Fig. 10 is a broken plan view of the control box cover.

45 Fig. 11 is a broken perspective view illustrating one section of the switch or controller construction in which operates a movable switch member illustrated in Fig. 8.

The signal controller above referred to by 50 which the operator, such as an aviator con-

trols the various signals above mentioned comprises a casing 10 of any suitable material and which may be mounted in a convenient position in the cockpit or other suitable place. The controller comprises an inner member indicated generally by the numeral 11 of a size to fit within the casing 10. The member 11 may be of one piece of bakelite or other material, the recesses and channels herein-after described being cut therein or molded, if the member is formed of moldable material.

Extending longitudinally of the member 10 is a channel 12, in the center of which is an opening 13 through which the various conductors from the signals pass to the respective switch members. The positive and negative current cables 14, 15 from a battery also are brought through the opening 13 and pass along the channel 12, one to each distributor plate 16, 17, each provided with the required number of contact screws 18, from which extend conductors to the various stationary switch members.

Extending parallel with the channel 12 are the channels 19, 20 and transversely of the member 11 are additional channels 21, five in number, in the present embodiment of the invention. The channel 12 and the intersecting channels 21 divide the member 11 into twelve sections indicated generally by the letters *a* to *l* respectively. As these sections are identical one only will be described specifically. A section is shown in perspective in Fig. 11 and comprises two spaced parallel upright walls 22, 22 which are beveled at the lower portions of their inner faces as shown. These walls have a pair of recesses therein, indicated at 23, 23, 24, 24, a post 25, being disposed between each pair of recesses 23, 24. An angular metal conductor 26, is mounted on the inward portion of the wall 22 and extends downwardly into the channel 23 and is secured in position by a bolt 27 as illustrated in Fig. 7. A similar conductor 28 is secured to the post 25 by a screw 29 and extends into the channel 24. Each conductor 26, 28 has a horizontally projecting tubular contact 30, 31 secured thereto and hereinafter further referred to. The conductors 26 have a number of contact screws 32 on the top thereof.

for attaching thereto the various wires which pass through the adjacent transverse channels 21 to the main longitudinal channel 12, thence through the opening 13 to the respective lamps controlled by the switch member. An additional contact screw is provided on each conductor 26 for a pilot light hereinafter referred to. The opposite wall of the unit has similar conductors, contact screws and wires which constitute the return circuit from the various lamps controlled by the particular switch being described.

To the contact screws 32 are attached wires 33 which pass through channels 21 to the outer channels 13a, thence into contact with the respective distributor plates 16, 17 which, as above mentioned, are connected by wires 14 with a battery (not shown). This arrangement of wires is suggested by the dotted lines of unit J of Fig. 1, the remaining wires being omitted for the sake of clearness. It will thus be seen that when the conductors 26, 28 of a unit are bridged, current will flow to the respective lamps controlled by such unit.

For bridging the said conductors 26, 28 selectively I have provided a slide member shown in enlarged perspective in Fig. 8. The slide is of insulating material and comprises a body 34 the lower portions of the side walls of which are flared slightly to provide a dovetail sliding fit with the tapered portions of the walls 22 of the unit. A stop 34a is positioned between the walls 22 to limit the movement of the slide in one direction, the stop being held in position by a screw 34b. Housed in the slide 34 are bridging members 35, secured in position by screws. The outwardly extending arms 36 of the members 35 are provided on corresponding faces with contact pins 37 which are arranged to frictionally seat in the tubular members 30, 31 of the conductors 26, 28 respectively when the slide is moved into circuit closing position. The slide is provided with an operating handle 38 by means of which the pilot can operate the slide. The handles project through openings 39 in the cover 40 of the casing 10.

In association with each switch unit there is provided a pilot lamp 41 one of which is illustrated in Fig. 2, the lamp being positioned in a socket carried in a recess 42. The cover 40 has lenses 43 for each of the pilot lamps, which lenses preferably are colored to correspond with the colors of the respective signal lamps.

By the construction described it will be seen that where the device is used for controlling a plurality of signalling lamps of an aeroplane, the pilot by moving any particular slide member 34 can energize the respective signals, such as for right or left turn, landing, various conditions of the vehicle, direction of flight, etc. Upon the actuation of a slide, the pilot light of such circuit will also

be lighted and as the pilot light lenses correspond to the colors of the respective signalling lenses, likelihood of mistake in actuating the wrong signal is largely eliminated.

Although I have shown and described certain features of my improvements for the purpose of illustrations, it will be apparent that various changes may be made without departing from the spirit of the invention, and therefore I do not wish to be restricted to the specific embodiment of the improvements herein shown and described except where limitations thereto appear in the appended claims.

I claim:

1. Switch mechanism for controlling a number of circuits comprising a plurality of switch units, each unit comprising a stationary switch member having a pair of spaced walls defining a channel therebetween, each wall having a contact member thereon forming a pair of terminals for one or more circuits, a second pair of terminals, one on each of said walls, said last named terminals being connected with a source of current, and a manually operable switch member slideable in said channel for bridging the terminals on each wall.

2. Switch mechanism for controlling a number of circuits comprising a plurality of switch units, each comprising a stationary member comprising a pair of walls and a manually movable member slideable between said walls, a pair of circuit terminals disposed in opposite relation one on each wall, a second pair of oppositely disposed terminals on said walls, said last named terminals being adapted for connection with a source of current, each of said terminals being provided with a tubular contact member, said sliding member having a pair of bridging members thereon each provided with a pin-like projection adapted to frictionally seat in one of said tubular contacts when said sliding member is moved to circuit closing position.

3. Switch mechanism comprising a pair of spaced walls each having two upstanding spaced portions on the top thereof, metal terminal members one secured to each of said portions and extending down one face thereof, and a slide member confined between said walls, said slide member having a pair of metal bridging members secured thereto each provided with laterally extending portions adapted to contact one with each of the downwardly extending portions of said terminals when said slide member is in circuit closing position.

4. Switch mechanism comprising a pair of spaced walls each having two upstanding spaced portions on the top thereof, metal terminal members one secured to each of said portions and extending down one face thereof, and a slide member confined between said

walls, said slide member having a pair of metal bridging members secured thereto each provided with laterally extending portions adapted to contact with said terminals when said slide member is in circuit closing position, said walls and said slide members having complementary flared portions for retaining said slide against removal.

5 In witness whereof I have subscribed my name.

10 FRED W. NOFFS.
